FIG. I.

FIG. II.

FIG. III.

FIG. V

FIG. IV

FIG. VI.

INVENTOR

ROBERT MEADE CRAIG,

By Robert M. Craig,
ATTORNEY

UNITED STATES PATENT OFFICE.

ROBERT M. CRAIG, OF WILKINSBURG, PENNSYLVANIA.

METALLIC-DENTURE-DRAWING DIE.

1,392,919.

Specification of Letters Patent. Patented Oct. 11, 1921.

Application filed June 19, 1919. Serial No. 305,422.

To all whom it may concern:

Be it known that I, ROBERT MEADE CRAIG, a citizen of the United States, residing at Wilkinsburg, in the county of Allegheny 5 and State of Pennsylvania, have invented a certain new and useful Improvement in Metallic-Denture-Drawing Dies, whereof the following is a specification, reference being had to the accompanying drawing.

10 It is the object of my invention to provide a die of special construction for drawing a primarily plane strip of sheet metal of uniform thickness to form an I-bar having opposite concave faces of substantially cylindroidal curvature, so that the opposite longitudinal edges of said bar are thicker than the middle portion thereof throughout its length. Such an I-bar is punched to form blanks for making denture backings to hold 15 porcelain tooth facings, in accordance with the process of making metallic denture backings which is claimed in my copending application Serial No. 305,421 filed June 19, 1919, for Letters Patent of the United States 20 25 1,353,565 granted September 21st, 1920.

My invention includes the various novel features of construction and arrangement herein specified and claimed.

In said drawing; Figure I is a perspective view of a strip of sheet metal of uniform thickness.

Fig. II is a perspective view of an I-bar drawn from said strip shown in Fig. I.

Fig. III is a perspective view of a pair 35 of dies, with said strip engaged therein.

Fig. IV is a central vertical sectional view of said dies and strip shown in Fig. III.

Fig. V is a front face view of said dies.

Fig. VI is a plan view of the lower die 40 member shown in Figs. IV and V.

Referring to Fig. I; it is to be understood that the strip of sheet metal 1 is of uniform thickness and uniform width throughout its length.

45 Referring to Fig. II; the I-bar 2, formed from said strip 1, has its opposite faces 3 concavely and substantially cylindroidally curved throughout its length so as to form a thin web 4 with opposite thick longitudinal edges 6 of the same transverse cross section, throughout its length.

Referring to Figs. IV, V and VI; the lower die block 7 has vertical recesses 8 in its ends for engagement with suitable parallel guiding supports in an ordinary die

press. Said die member 7 has the trough shaped passage 10 extending transversely across it, intermediate of its length, and of the desired width of said I-bar 2. Said passage 10 has the convex ridge 11, intermediate of its length and of the desired cylindroidal configuration of the lower face of said I-bar 2; but said passage slopes both ways, in the direction of its length, so as to be deeper at both its front and rear than at 60 said ridge and thus afford suitable clearance to receive said strip 1 at the front face of said die member, and permit the free passage of said I-bar 2 at the rear face of said die member. 70

The upper die block 14 has vertical recesses 15 at its opposite ends, registering with the recesses 8, for engagement with said supports of the die press, and has the downwardly extending convex projection 17 75 registering with said passage 10. Said projection, at its shoulder 18, is of the desired cylindroidal configuration of the upper surface of said I-bar 2, but slopes therefrom toward its front face, as indicated at 19, to 80 facilitate the traverse of said strip 1. Said projection 17 is cut away, as indicated at 20, in its extent rearwardly from said shoulder 18, to afford clearance for the withdrawal of said I-bar 2. 85

In operating said drawing die members 7 and 14, to draw the I-bar 2 aforesaid; they are first separated to a sufficient vertical extent to permit the strip 1 to extend loosely between them to such length as to permit its forward end 22 to be engaged by a suitable gripping device, by which it may thereafter be drawn through said passage 10. Thereupon, said upper die block 14 is pressed downwardly, conveniently by screws 21 in 95 spaced relation intermediate of its length, until the two members 7 and 14 are in the position shown in Fig. V. Thereupon, said strip is drawn through said passageway, in the direction of the arrow shown in Fig. III, 100 and thus reduced to form the desired I-bar 2.

Referring to Fig. V; it may be observed that the opposite edges of said passage 10 are not parallel, but so inclined, vertically, that the upper surface of said I-bar is 105 slightly wider than the lower surface. That peculiar configuration of said passage, and consequent formation of said I-bar, is designed to permit slight deformation of the thick edges 6 of said bar by the operation 110

of punching blanks therefrom, by means of the improvement in processes of making metallic denture backings, which is claimed in said Letters Patent of the United States 5 No. 1,353,565, the operation of forming such blanks being a combined punching and swaging operation which leaves the blanks with their opposite edges parallel, but of slightly less thickness than said thick edges 10 6 of said bar; thus rendering the metal of said blanks less ductile, and consequently more rigid, at such edges, than the metal of said bar.

However, I do not desire to limit all of 15 my claims to such construction and arrangement of drawing dies as to produce a bar the opposite longitudinal edges of which are not parallel. Therefore, I do not desire to limit myself to the precise details of construction and arrangement herein set forth, 20 as it is obvious that various modifications may be made therein without departing from the essential features of my invention, as defined in the appended claims.

25 It is to be noted that the ordinary mechanism for forming I-bars includes several pairs of respectively differently shaped die rollers, between which the metal is successively passed while said rollers are positively 30 rotated, to effect successive steps in the reduction of the metal to the desired form, and that my improved mechanism is advantageous not only in that it is less costly to construct, but may be used to effect the 35 desired result by a single operation. However, it is to be understood that a metal strip 1 may be reduced to the form 2 by a series of drawing operations with my improved mechanism; the opposed die members 40 7 and 14 being progressively adjusted, toward each other, accordingly.

I claim:

1. In mechanism for forming an I-bar from a primarily plane strip of sheet metal; 45 the combination with a die member having a trough shaped passage with a ridge, extending transversely to the length of said passage, of convex configuration corresponding with the desired cylindriform configuration 50 of one face of the bar to be drawn; said passage being inclined in both directions from said ridge so as to afford clearance for the introduction of said strip at the front of said passage and clearance for the withdrawal 55 of said bar at the rear of said passage; the opposite longitudinal edges of said passage being parallel with each other in the direction of its length and inclined to each other transversely to its length; of 60 another die member having a projection registering with said passage and having a shoulder, extending transversely to the length of said passage, of convex configuration corresponding with the desired cylindriform configuration 65 of the proximal face

of the bar to be drawn; said projection being inclined from said shoulder toward the front of said die member, to afford clearance for the introduction of said strip, and said projection being cut away from said shoulder to the rear face of said die member to afford clearance for said I-bar; said die members having similar and registered recesses at their opposite ends for engagement with parallel guiding supports; whereby said members are adjustable in variable spaced relation with each other, to vary the dimensions of said passage between said ridge and shoulder, and thus vary the deforming effect of said die members upon 80 said strip.

2. In mechanism for forming an I-bar from a primarily plane strip of sheet metal; the combination with a die member having a trough shaped passage with a ridge extending transversely to the length of said passage, of convex configuration corresponding with the desired cylindriform configuration of one face of the bar to be drawn; said passage being inclined in both directions from said ridge so as to afford clearance for the introduction of said strip at the front of said passage and clearance for the withdrawal of said bar at the rear of said passage; the opposite longitudinal edges of said passage being parallel with each other in the direction of its length; of another die member having a projection registering with said passage, and having a shoulder, extending transversely to the length of said passage, of convex configuration corresponding with the desired cylindriform configuration of the proximal surface of the bar to be drawn; said projection being inclined from said shoulder toward the front of said die member, to afford clearance for the introduction of said strip, and said projection being cut away from said shoulder to the rear face of said die member to afford clearance for the introduction of said strip, and said projection being cut away from said shoulder to the rear face of said die member to afford clearance for said I-bar; said die members having similar and registered recesses at their opposite ends for engagement with guiding and supporting means; whereby said members are adjustable in variable spaced relation with each other, to vary the dimensions of said passage between said ridge and shoulder, and thus vary the deforming effect of said die members upon said strip.

3. In mechanism for forming an I-bar from a primarily plane strip of sheet metal; the combination with a die member having a trough shaped passage with a ridge extending transversely to the length of said passage, of convex configuration corresponding with the desired configuration of one face of the bar to be drawn; said passage being inclined in both directions from said ridge so as to afford clearance for the introduction of said strip at the front of said 130

passage and clearance for the withdrawal of said bar at the rear of said passage; of another die member having a projection registering with said passage, and having a shoulder, extending transversely to the length of said passage, of convex configuration corresponding with the desired configuration of the proximal surface of the bar to be drawn; said projection being inclined from said shoulder toward the front of said die member, to afford clearance for the introduction of said strip, and said projection being cut away from said shoulder to the rear face of said die member to afford clearance for said I-bar; said die members having similar and registered recesses at their opposite ends for engagement with guiding and supporting means; whereby said members are adjustable in variable spaced relation with each other, to vary the dimensions of said passage between said ridge and shoulder, and thus vary the deforming effect of said die members upon said strip.

4. In mechanism for forming an I-bar from a primarily plane strip of sheet metal; the combination with a die member having a trough shaped passage with a ridge extending transversely to the length of said passage; said passage being inclined so as to be deeper at each end than at said ridge; the opposite longitudinal edges of said passage being parallel with each other in the direction of its length and inclined to each other transversely to its length; of another die member having a projection registering with said passage, and having a shoulder; said projection being inclined from said shoulder toward the front of said die member; said die members having registered recesses for engagement with guiding means; whereby said members are adjustable in variable spaced relation with each other, to vary the dimensions of said passage between said ridge and shoulder, and thus vary the deforming effect of said die members upon said strip.

5. In mechanism for forming an I-bar from a primarily plane strip of sheet metal; the combination with a die member having a trough shaped passage with a ridge extending transversely to the length of said passage; said passage being inclined so as to be deeper at each end than at said ridge; the opposite longitudinal edges of said passage being parallel with each other in the direction of its length; of another die member having a projection registering with said passage, and having a shoulder; said projection being inclined from said shoulder toward the front of said die member; said die members having registered recesses for engagement with guiding means; whereby said members are adjustable in variable spaced relation with each other, to vary the dimensions of said passage between said

ridge and shoulder, and thus vary the deforming effect of said die members upon said strip.

6. In mechanism for forming an I-bar from a primarily plane strip of sheet metal; the combination with a die member having a trough shaped passage with a ridge extending transversely to the length of said passage; said passage being inclined so as to be deeper at each end than at said ridge; of another die member having a projection registering with said passage, and having a shoulder; said projection being inclined from said shoulder toward the front of said die member; said die members having registered recesses for engagement with guiding means; whereby said members are adjustable in variable spaced relation with each other, to vary the dimensions of said passage between said ridge and shoulder, and thus vary the deforming effect of said die members upon said strip.

7. In mechanism for forming an I-bar from a strip of metal; the combination with a die member having a trough shaped passage with a ridge extending transversely to the length of said passage of convex configuration corresponding with the desired cylindriform configuration of the proximal face of the bar to be drawn; the opposite longitudinal edges of said passage being parallel with each other in the direction of its length and inclined to each other transversely to its length; of another die member having a projection registering with said passage, and of convex configuration corresponding with the desired cylindriform configuration of the proximal face of the bar to be drawn; said members being adjustable in variable spaced relation with each other, to vary the dimensions of said passage between said ridge and shoulder, and thus vary the deforming effect of said die members upon said strip.

8. In mechanism for forming an I-bar from a strip of metal; the combination with a die member having a trough shaped passage with a ridge extending transversely to the length of said passage of convex configuration corresponding with the desired cylindriform configuration of the proximal face of the bar to be drawn; the opposite longitudinal edges of said passage being parallel with each other in the direction of its length; of another die member having a projection registering with said passage, and of convex configuration corresponding with the desired cylindriform configuration of the proximal face of the bar to be drawn; said members being adjustable in variable spaced relation with each other, to vary the dimensions of said passage between said ridge and shoulder, and thus vary the deforming effect of said die members upon said strip.

9. In mechanism for forming an I-bar from a strip of metal; the combination with a die member having a trough shaped passage with a ridge extending transversely to the length of said passage of convex configuration corresponding with the desired concave cylindriform configuration of the proximal face of the bar to be drawn; of another die member having a projection registering with said passage, and of convex configuration corresponding with the desired concave cylindriform configuration of the proximal face of the bar to be drawn; said members being adjustable in variable spaced relation with each other, to vary the dimensions of said passage between said ridge and shoulder, and thus vary the deforming effect of said die members upon said strip.
10. Mechanism constructed and arranged

to form an I-bar from a primarily plane strip of metal; including a die member having a trough shaped passage with a ridge extending transversely to the length of said passage corresponding with the desired concave configuration of the proximal face of the bar to be drawn; of another die member having a projection registering with said passage, and corresponding with the desired concave configuration of the proximal face of the bar to be drawn; whereby said strip may be reduced to form said I-bar by drawing it through said passage. 25

In testimony whereof, I have hereunto signed my name at Wilkinsburg, Pennsylvania, this sixth day of November, 1918. 30

ROBERT M. CRAIG.
